Primary Examiner—Cynthia E Ramirez

(74) *Attorney, Agent, or Firm*—Westerman, Hattori, Daniels & Adrian, LLP.

(57) **CLAIM**

The ornamental design for a linking pin for power transmitting chain, as shown and described.

DESCRIPTION

FIG. 1 is a front elevational view of a linking pin for power transmitting chain showing our new design;

FIG. 2 is a rear elevational view thereof;

FIG. 3 is a side view, with the other side being a mirror thereof;

FIG. 4 is a top view thereof;

FIG. 5 is cross-sectional view taken along lines A—A in FIG. 1;

FIG. 6 is a cross-sectional view taken along lines B—B in FIG. 1;

FIG. 7 is a cross-sectional view taken along lines C—C in FIG. 1;

FIG. 8 is a front perspective view thereof;

FIG. 9 is a rear perspective view thereof; and,

FIG. 10 is a reference view in use situation.

The broken lines show an environmental structure and do not form any part of the claimed design.
